UNITED STATES PATENT OFFICE.

JACOB H. EMMERT, OF PORTLAND, OREGON.

FOLDING HAMMOCK-SUPPORT.

No. 907,687.

Specification of Letters Patent.

Patented Dec. 22, 1908.

Application filed June 29, 1907. Serial No. 381,536.

To all whom it may concern:

Be it known that I, JACOB H. EMMERT, a citizen of the United States, and a resident of Portland, in the county of Multnomah and 5 State of Oregon, have invented a new and useful Improvement in Folding Hammock-Supports, of which the following is a specification, reference being had to the accompanying drawings as constituting a part 10 thereof.

My invention has for its object to obtain a folding hammock-support, inexpensively made of stock material, adjustable to suit the varying lengths of hammocks, and easily 15 transportable.

I attain my object by the construction and arrangement of parts illustrated in the accompanying drawings.

In such drawings, Figure 1 is a perspective of my device, arranged as in practice to support a hammock; Fig. 2 is a partial side elevation; Fig. 3 is a sectional detail of the leg hinges; Fig. 4 is a detail of one of the hooks, shown in the preceding figures, from 20 which the hammock is supported at its ends; Fig. 5 is a partial side elevation of a modified type of construction of my device; and Fig. 6 is a sectional detail of the leg hinges used in such modified type.

30 The letters designate the parts described.

My device is made of piping and pipe-couplings, commonly found in stock with dealers of plumbers' supplies. The legs a , b , a' , b' , consist of suitable lengths of pipe, the lower ends of which are preferably closed by means of caps c , so as to keep out dirt; and on the upper ends of the legs (the pipe lengths being threaded at both ends) are secured tee-couplings d , d' . The two legs are 35 joinedly arranged side by side, as shown, by means of an intermediate bushing e , having an exterior thread, and a smooth inner bore or surface, in which are inserted the reduced ends f' of the horizontal, telescoping rod f .

40 The latter is conveniently constructed of two pieces of pipe, one (f^2) of smaller diameter than and adapted to be slidably inserted in the bore of the other. A reduced end is obtained at the outer end of the pipe 45 of larger diameter, by inserting a rod in said outer end thereof; the parts being threaded. The smaller pipe-section f^2 is of a size to fit the eye of the bushing of the tee-couplings for the legs a' , b' . A collar g is provided on 50 the smaller pipe-section f^2 to limit the distance the same will enter the eye of the hinge-

joints of said legs a' , b' ; and the shoulder f^3 serves the same purpose as the collar g . It will be noted that the legs a , b , a' , b' , when spread apart and folded together again, 60 pivot on the thread of the bushing, which construction I have adopted, so as to hold said tee-coupling-joints against lateral displacement. Intermediate of each pair of tee-couplings d , d' , I place on their connecting bushing a ring h , provided with an eye h' , and a hook i , the parts being arranged to allow the hook sufficient freedom of motion to facilitate the attachment of the supporting end of the hammock thereto. To limit 65 the distance which the legs a , b , a' , b' , spread apart I provide adjustable means. A chain j , is fastened by a clamp k to one leg, and caught on a hook l , secured on the opposite leg. 70

When my device is to be arranged in condition for transportation, the telescoping rod f is removed, the smaller section thereof pushed into the larger, the legs a , b , a' , b' arranged side by side, and then the whole 80 may be wrapped together with the hammock, in a parcel convenient for carrying about, or shipping. 75

Another feature incidental to the described construction is, one section of my hammock 85 supporter may be used as a tripod in camp, from which to support camping utensils, the parts, in that case, being so arranged as to rest on the ground, upon one end of the telescoping pipe f , and the legs of one section end 90 of the device. The hook i , under such conditions, providing convenient means from which to suspend the cooking utensil.

In Figs. 5 and 6 I show a modified type of construction, and preferred by me. The 95 general features of the joining of the legs are the same, but the two sections of connecting pipe f , f^2 , described in the first mentioned type are replaced by two sections of pipe m , m' , of the same diameter and connected at 100 their inner ends by a sleeve n , brazed on one pipe end and into which the other pipe end is inserted, when the parts are assembled. The bore of both tee-coupling joints d^2 , d^3 , of the legs a^2 , b^2 , and a^3 , b^3 , is of the same diameter, 105 and the outer ends of the pipe sections m , m' are slidably inserted therein. To secure the inserted pipe ends against lateral movement in the eyes of said tee-couplings, I make the rings h^2 with a locking-hook o , inserted in one 110 of a series of holes p , therefor made in the pipe ends. The rings h^2 are also provided

with hooks *i*, above mentioned, on which to hang the hammock, or cooking utensil. The advantage of the last described type of construction is, the parts are somewhat easier made and are less affected by exposure to the weather.

Besides the uses of my device above set forth, the legs could be brought close together, so as to be suitable to suspend a child's swing from the connecting-rod; and furthermore the supporting-frame could be used as the frame of a canopy.

For cheaper constructions, wooden sticks could be used instead of pipe-lengths for legs, and likewise a wooden pole could be used instead of the pipe connecting-rod.

To prevent the inadvertent telescoping of the smaller pipe *f*² into the larger pipe *f*, in the type of construction illustrated in Fig. 1, I fasten a pin *q* by means of collar and chain *r* and make the smaller pipe with holes *s*, in which to insert said pin.

I claim:

1. A hammock supporter comprising a pair of legs for each end, a tee-coupling on the upper end of each leg, bushings inserted in and jointedly connecting the tee-couplings of each pair of legs, a two-part separable connecting-rod, the ends of which are slidably inserted in the eyes of said tee-couplings, means adapted to lock the slideable ends of the connecting-rod in place in said tee-coupling, and supporting hooks on the tee-coupling.

2. A hammock-supporter comprising a pair of legs for each end, a tee-coupling on the upper end of each leg, bushings inserted in and jointedly connecting the tee-coupling.

lings of each pair of legs, a two-part separable connecting-rod, the ends of which are slidably inserted in the eyes of said tee-couplings, a hook arranged to be inserted in one of a series of perforations therefor provided in the ends of the connecting-rod, to lock the same in place in said tee-couplings, and supporting-hooks on the tee-couplings.

3. A hammock-supporter comprising a pair of legs for each end, a tee-coupling on the upper end of each leg, bushings inserted in and jointedly connecting the tee-couplings of each pair of legs, means limiting the lateral extension of the legs, a two-part separable connecting-rod, the ends of which are slidably inserted in the eyes of said tee-couplings, a hook arranged to be inserted in one of a series of perforations therefor provided in the ends of the connecting-rod, to lock the same in place in said tee-couplings, and supporting-hooks on the tee-couplings.

4. In a hammock supporter, the combination of a pair of legs for each end, tee-couplings on the upper ends of each leg, bushings inserted in and jointedly connecting said tee-couplings of each pair of legs, a connecting-rod having perforations in its ends and adapted to be slidably inserted in said tee-couplings, collars inserted on the bushing intermediate of each pair of tee-couplings, pendant supporting-hooks on said collars, and hooks secured to said collars arranged to be inserted in perforations in the ends of the connecting-rod.

JACOB H. EMMERT.
